UNITED STATES PATENT OFFICE.

FREDERICK U. BOWERS, OF SAN FRANCISCO, CALIFORNIA.

ARTIFICIAL DENTURE.

1,293,627.

Specification of Letters Patent.

Patented Feb. 4, 1919.

Application filed December 18, 1917. Serial No. 207,647.

To all whom it may concern:

Be it known that I, FREDERICK U. BOWERS, a citizen of the United States, residing at the city and county of San Francisco and State of California, have invented new and useful Improvements in Artificial Dentures, of which the following is a specification.

This invention relates to artificial dentures or dental plates, and pertains especially to the production of a metal plate which is of light weight, sanitary, well fitting and comfortable to the wearer, and in which there is no rubber whatever exposed except the outer labial surface, which latter may be of pink rubber, colored synthetic porcelain, or the like, to simulate the color of the gums; the interior or palatal surface of the plate being of a built-up metal structure.

The usual method of constructing a set of teeth with metal backing, is to employ a gold or other metallic plate of considerable thickness and strength, and arranged in a bed of vulcanized rubber around the rim thereof in which the teeth are set. The rubber is exposed to the mouth both at the outside and inside of the teeth and the metallic plate is necessarily of such size and weight as to be expensive and difficult to shape and cumbersome and tiresome to the wearer.

Having reference to the accompanying drawings,

Figure 1 is a perspective view of a dental plate.

Figs. 2 to 11 inclusive show successive steps in the process.

Fig. 12 is a rear view of the model.

Fig. 13 is a detail view of the base plate.

Fig. 14 is a detail view of the palatal plate.

Fig. 15 is a detail section of the base and palatal plates showing them bedded together.

According to the present invention two gold, or other metallic plates A and B of extreme thinness are employed in place of the single comparatively heavy plate heretofore used. Plate A is the base plate and B represents the palatal plate, which latter in the finished product is brought up close to the teeth C and wedged snugly thereagainst, there being a thin layer of vulcanized rubber D between the plates and in which the teeth are embedded. To produce such a denture I proceed as follows:

1. *Making the impression.*—An impres-

sion 10 of the mouth is made in the usual manner.

2. *Making the model.*—The impression 10 obtained is built up on the outside to provide a receptacle of sufficient depth into which the base metal is poured to obtain the model which is represented at 11. This model is made of zinc or Mellot's metal. (See Fig. 4.)

3. *Swaging the base plate.*—Upon the model 11 thus obtained I next swage the base plate A in the manner well known in the art; being careful to obtain a correct molding of the plate to the configurations of the mouth in which the plate is later to be inserted. (See Fig. 5.)

4. *Attaching the anchorages.*—The base plate A is then removed from the model 11, and there is soldered on the lingual side of the alveolar ridge of the base plate a number of small loops 2 to hold the rubber; these loops being provided preferably by a suitably looped wire. (See Fig. 13.)

5. *Obtaining the bite.*—I next obtain the bite by placing a roll of wax on the alveolar ridge of the base plate and introducing the whole into the mouth requiring the patient to bite upon it, thereby obtaining an impression of the lower teeth in the wax.

6. *Articulating.*—The whole is then removed from the mouth and placed upon the top part of an articulator in the usual manner; that is, the portion of the bite containing the imprint made by the natural teeth is filled with plaster-of-Paris, allowed to set and the wax then removed; the plaster portion remaining being a replica of the natural teeth from which the bite was made. The artificial teeth which are to form part of the finished plate are set up in wax on the base plate and built up to the proper contour and length.

7. *Preparing to swage the palatal plate.*—The model 11 is then put into a ring swager 13. Upon the model is laid the base plate having the teeth and wax thereon. Dental plaster 14, or some other quick hardening substance is poured into the ring 13 around the outside of the teeth and over the top surface of the teeth and allowed to set. All plaster, however, is excluded from the inside or palatal surface. The object of this outside reinforcing to the teeth by means of the plaster is to hold the teeth firmly in position and support them from the outside so that they cannot be disturbed by the act of swag-

ing the palatal plate B, which is to cover the palatal surface (see Fig. 7).

8. *Swaging the palatal plate.*—I now proceed to swage the palatal plate B by swaging, removing, cutting, trimming, re-swaging and so on, until this palatal plate is so swaged and shaped that definite points between the teeth and over the heels of the back plate A are such that there is no wax exposed on the palatal surface, or on the heels of the plate A. This palatal plate B should extend approximately $\frac{1}{16}$ " beyond the base plate.

9. *Attaching loops to the palatal plate.*—15 After swaging, remove the palatal plate and solder several little loops 3 to the upper side thereof around the entire plate about $\frac{3}{16}$ " from the edge (see Fig. 14). These loops may be formed out of a single strip of wire 20 and for the same purpose as the loops 2 above-mentioned on the base plate A; that is, to form an anchorage for the rubber. With these loops in place on the palatal plate, the latter is again re-swaged into position until its perimeter is shown to have a close fit against and into the interstices between the teeth.

10. The palatal plate and the back plate with teeth still in position, and model, are 30 then all removed from the swaging ring and cleaned of plaster and placed in the bottom half 15 of a flask (see Fig. 8). The flask around the model is filled with plaster 16 up to the exposed base of the teeth. That is, 35 the teeth are not covered with this first plaster filling, but only around the model and the wax in which the teeth are temporarily embedded are covered with the plaster. This plaster is allowed to set and is then 40 painted with a separating fluid. The top half 17 of the flask is then placed in position and the flask is filled full with plaster 18, and the top 19 of the flask applied; the last plaster filling being allowed to set (see 45 Fig. 9).

11. When the plaster is thoroughly dry the flask is placed in water and brought to a boil thereby softening the wax which temporarily holds the teeth. The flask is then 50 opened up and the parts separated; the teeth and the palatal plate being firmly embedded in the plaster body 18; these parts all being carried by the top half of the flask, the lower half of the flask containing the model and 55 the base plate.

12. *Packing the dental rubber.*—As the base plate A still adheres to the portion of the denture carried by the lower half of the flask, the top, carrying the palatal plate and 60 the teeth embedded in the plaster body 18, is lifted off and the soft wax removed from the teeth and the two plates A and B in any suitable manner. Dental rubber is then packed around the roots of the teeth and 65 smeared over the adjacent faces of the two

plates A and B; small waste gates or ports 20 being cut at the back of the model for the outlet of excess rubber.

13. *Vulcanizing.*—The flask is then put together with pressure and vulcanizer, after 70 which the excess rubber is removed from the back of the plates and the overlapping back edge 5 of the palatal plate is burnished over the edge of the base plate A, thereby covering the joint of the two plates. 75

The denture is now ready for use.

As a result of this structure considerable saving in metal is effected, the rubber bed at the inside of the teeth is sealed, and there is given the appearance of a solid gold plate; 80 the two thin sheets of metal A and B are lighter and are stronger than the single thick sheet heretofore used, and also are much easier to shape. The only rubber visible is the portion E around the outside, giving a 85 color in imitation of the gums.

Having thus described my invention, what I claim and desire to secure by Letters Patent is:—

1. The method of forming artificial dentures which comprehends first the making of 90 an impression, then the making of a model from the impression, then swaging a base plate on the impression, then obtaining a bite, articulating the teeth on the base plate, 95 then placing the base plate with the articulated teeth upon the model and building up with plaster around the outside of the model and teeth and separating the plaster and allowing the plaster to set so as firmly to 100 hold the teeth against displacement when outward pressure thereon is applied, then swaging a palatal plate over the palatal surface included by the teeth, placing the model and base plate with teeth thereon and palatal 105 plate into a flask, packing with plaster and separating in the usual manner, and then packing the space between the palatal plate, back plate and around the teeth with dental rubber, subjecting the parts to pressure to 110 extrude the excess rubber, then vulcanizing the rubber and burnishing the plate.

2. The manufacture of an artificial denture which includes as a step therein the preparation of a palatal plate by swaging 115 against the teeth set in wax by supporting the teeth by a body of plaster around the outside thereof against the swaging action of the palatal plate against the teeth.

3. An artificial denture which comprises 120 in combination a back plate suitably shaped to the impression of the mouth with a row of teeth on the alveolar ridge of the plate, and a palatal plate swaged between and against the teeth, the palatal plate entirely 125 covering the palatal surface, and a thin layer of vulcanized rubber between the two plates and in which the teeth are embedded, said plates being of extreme thinness with little individual inherent rigidity and with the 130

rear edge of the palatal plate burnished over the edge of the base plate covering the joint therebetween.

4. An artificial denture which comprises
5 in combination a continuous back plate shaped to the impression of the mouth and having an alveolar ridge formed thereby, a row of teeth resting directly upon this ridge, a palatal plate fitting directly between the
10 teeth and bearing with its opposite edges thereagainst, said plate being spaced from

the back plate, and a layer of vulcanized rubber between said plates and covering the alveolar ridge in which the teeth are embedded.

15

In testimony whereof I have hereunto set my hand in the presence of two subscribing witnesses.

FREDERICK U. BOWERS.
